ANTITAIL SPIN DEVICE

Filed May 2, 1930

By *Harold L. Staggins* Attorney

UNITED STATES PATENT OFFICE

LEWIS J. TETLOW, OF HOLYOKE, MASSACHUSETTS

ANTITAIL SPIN DEVICE

Application filed May 2, 1930. Serial No. 449,275.

This invention relates to airplanes and more particularly to means for preventing the plane from going into a tail spin and comprises a tail lifting device secured to the elevators and adapted to form an air pressure zone against the bottom face of the stabilizer whereby a sufficient pressure is exerted upon the bottom face of the stabilizer which will automatically raise the tail end of the plane to normal flying position.

An object of the present invention is the provision of means which may be readily secured to the elevators of an airplane and simultaneously controlled from the operator's cockpit by a single lever to create an upward pressure upon the bottom face of the stabilizer when the elevators are swung downwardly.

Another object of the present invention is the provision of one or more of these tail lifters to each elevator in order to obtain the maximum pressure possible against the bottom face of the stabilizer to assist in immediately raising the tail end of the plane when the pilot observes on the instrument board the initial slipping of the plane.

The greatest hazard in aviation at the present time is what is known as the tail spin and it is practically impossible to right a machine once it goes into a tail spin. It is with this thought in mind that the present invention has been designed in order to lessen the chance of a plane going into a tail spin, and which will enable a pilot to readily right the plane to its normal flying position upon the instrument showing that the plane is beginning to slide. Upon observing this indication on the instrument board, the pilot can immediately throw his control lever to drop the elevators so as to create air pressure zones upon the bottom face of the stabilizer due to the air pressure created by the force of air emitting thru the tail lifters in a concentrated area which force is sufficient to check the slipping and immediately raise the tail end of the plane to its normal flying position.

In the drawings:

Figure 1 is a top plan view of an airplane fuselage having pipes on the outside with the

controls passing thru for controlling the tail lifters of the present invention.

Figure 2 is a side elevation of an elevator showing the tail lifting means secured thereto.

Figure 3 is a transverse section thru one of the tail lifters.

Figure 4 is a plan view of the elevators showing one or more of the tail lifters applied thereto.

Figure 5 is a side elevation of one of the tail lifters showing the beveled edges.

Figure 6 is a transverse section of an elevator showing a modified form of tail lifter.

Referring more in detail to the drawings 10 indicates the fuselage of an airplane having the usual cockpit 11 and control lever 12, and also including the stabilizer 13, rudder 14, and elevators 15. Suitable tubes 16 are provided on the fuselage to receive the control wires 17 and 18 from the rudder 14 and elevators 15 thru which the control wires pass to the control lever 12.

The feature of the present invention resides in providing upon the elevators 15 suitable tail lifters 19. These tail lifters 19 may be of any desired shape and accomplish the same result but for the purpose of illustration, I have shown in the drawings a cylindrical tail lifter. However, it is to be understood that I do not limit myself to such a construction. The cylindrical tail lifter shell 19 shown is provided with a central longitudinal slot 20 dividing the same into two substantially equal semi-circular portions 21 and 22. The top portion 21 is of less length than the bottom portion 22 and has its forward edge beveled as at 23 so as to offer as little resistance as possible when the elevators are swung downwardly to right the plane to its normal flying position. The bottom portion 23 extends forwardly of the upper portion and is beveled off as at 24 so as to form an air pressure zone with the bottom face of the stabilizer 13 when the elevators are swung downwardly. These tail lifters are detachably secured to the elevators by slipping the end portion of the elevators thru the slot 20 with the inclined edges 23 and 24 facing in close proximity to the hinged

portion of the elevators adjacent the stabilizer whereby when the stabilizer is tilted downward the lower half of the tube 19 is substantially closed. Suitable threaded openings are 5 provided in the tail lifters to receive the screw 25 which passes thru openings in the elevators 15.

In some instances it may be desirable to attach more than one of these tail lifters to each 10 elevator as shown in Figure 4. This is to take care of the larger planes and give greater raising power to take care of the increased weight of the larger planes. However, the construction of the tail lifters is identical 15 and the result accomplished is the same. It may also be desirable to eliminate the upper portion 21 and if such is the case the tail lifter may be constructed as shown in Figure 6. This lifter is applied to the bottom face 20 of the elevators and may be of any desired shape or contour and is provided with flanges 26 for securing the same to the elevators and also includes the beveled edge 24 for resting closely the bottom face of the stabilizer so 25 as to form an air pressure zone to create an upward pressure on the stabilizer for raising the tail end of the plane to its normal flying position.

With a plane equipped with the tail lifters 30 of the present invention the danger of tail spinning is greatly reduced. Should a pilot be flying along under normal conditions and then something happen that would cause the plane to begin sliding it would be noticed immediately on the instrument board. The pilot would then move his control lever 12 so as to throw the elevators 15 downwardly and due to the fact that the elevators are provided with one or more of the tail lifters, 35 as the case may be, air is passed thru the lifters 19 and concentrated against the bottom face of stabilizer 13 due to the forward edge 24 of the lower portion 22 of the lifters terminating in close proximity to the bottom 40 face of the stabilizer to substantially close the lower half of the tube 19 and forming an air pressure zone which assists in raising the tail end of the plane to its normal flying position. Thus it will be seen that the possibility 45 of tail spinning is greatly reduced when a plane is equipped with the tail lifters of the present invention.

What I claim is:

- 50 1. In an airplane having fuselage, a stabilizer, a rudder, and elevators; air current actuated tail lifting means attached to said elevators.
2. The device of claim 1 in which the tail lifting means defines a passageway to create an upward pressure upon the bottom face of the stabilizer when the elevators are moved downwardly.
3. The device of claim 1 which the tail 55 lifting means comprises a hollow member on

each elevator the axes of said members being parallel to the plane of the elevator.

4. The device of claim 1 in which the tail lifting means comprises a hollow member on each elevator having a beveled end adapted 70 to form an air pressure zone with the bottom face of the stabilizer.

5. The device of claim 1 in which the tail lifting means forms an air duct both above and below the elevator.

6. The device of claim 1 in which the tail lifting means is a tubular member bisected longitudinally by the elevator.

7. The device of claim 1 in which a plurality of tail lifting means is attached to each elevator.

8. The device of claim 1 in which the tail lifting means forms an air duct on the bottom face of the elevator.

9. The device of claim 1 in which the tail lifting means is a slotted tubular member having a beveled end.

10. The device of claim 1 in which the tail lifting means comprises a tubular member equally spaced above and below the elevator 90 and having the lower portion extending forwardly of the upper portion.

11. An airplane comprising a fuselage, a stabilizer, a rudder, control mechanism, elevators and air current actuated tail lifting 95 means detachably secured to said elevators at each side of the fuselage.

12. In an airplane having a stabilizer at the rear of the fuselage and having separate elevators hingedly connected to the stabilizer, a device to deflect the rear or tail of the plane as a tail spin is about to be initiated, said device consisting of an elongated shell longitudinally positioned on the bottom surface of each elevator forming with said surface an air passage terminating in proximity to the hinged end, whereby as the plane tends to move rearwardly, a downward movement of both elevators will cause the air passing thru the shells to be directed against the bottom surface of the stabilizer to resist the tendency of the tail of the plane to sink by gravity in order to give the pilot time to right the plane.

In testimony whereof I affix my signature. 115
